UNITED STATES PATENT OFFICE.

ARNO A. EWALD, OF OAKFIELD, WISCONSIN.

AIR-SUPPLY STATION.

1,427,450.

Specification of Letters Patent: Patented Aug. 29, 1922.

Application filed February 9, 1920. Serial No. 357,475.

To all whom it may concern:

Be it known that I, ARNO A. EWALD, a citizen of the United States, residing at Oakfield, in the county of Fond du Lac and State 5 of Wisconsin, have invented certain new and useful Improvements in Air-Supply Stations; and I do declare the following to be a full, clear, and exact description of the invention, such as will enable others skilled 10 in the art to which it appertains to make and use the same.

My invention relates to the inflation of motor vehicle and bicycle tires and more particularly to an inflating device adapted to 15 form a so-called free air station; and my principal object is to provide a station of this character in which the air hose is suspended from a normally raised but downwardly movable arm, so as to at all times be 20 readily accessible and to prevent tangling and soiling as now commonly occurs when the hose lies on the floor of the garage, on the sidewalk or street, or is confined in a pit.

Another object is to provide means for cutting off the air supply until the arm is lowered by pulling on the hose.

A still further object is the provision of an elastic connection for actuating the control for the air supply means, and for assisting in raising the hose carrying arm.

Yet another object is to provide a device of the class described in which all working parts are effectively protected against both 35 tampering and weather conditions.

A still further object is to provide a device of the character set forth which may be installed with ease on the ceiling or wall of a garage or other building, and which will be 40 provided with a swinging member adapted to normally hold a suspended length of hose in a position retracted from the line of vehicle travel, and out of contact with the ground, but in a position to be readily 45 grasped and pulled outwardly and downwardly to a position for use, said swinging member being adapted to travel over a vehicle canopy to carry the hose to both ends and sides of the vehicle.

Yet another object is to provide novel 50 coin-controlled means for locking the device against operation until a nickel or other predetermined coin is inserted.

With the foregoing in view, the invention 55 resides in the novel construction and ar-

angement of parts hereinafter described and claimed, the descriptive matter being supplemented by the accompanying drawings.

Figure 1 is a perspective view showing 60 the device in use.

Fig. 2 is a side elevation with parts in vertical section.

Fig. 3 is approximately a central vertical 65 section of the entire device.

Figs. 4 and 5 are horizontal sections on the planes indicated by the lines 4-4 and 5-5 respectively of Fig. 3.

Fig. 6 is a diagram showing a different 70 form of construction.

Fig. 7 is a view similar to Fig. 1 showing the device installed on a ceiling.

Fig. 8 is a vertical section of the construction shown in Fig. 7.

Fig. 9 is a view similar to Fig. 8 but illustrating 75 the manner of supporting the device on a vertical wall.

Fig. 10 is a detail vertical section showing the application of a coin-controlled lock to prevent discharge of air until a coin is inserted.

Fig. 11 is an enlarged elevation of the coin-controlled lock with parts in section.

Figs. 12 and 13 are horizontal sections on the planes indicated by the lines 12-12 and 85 13-13 of Fig. 11.

In the drawings above briefly described, the numeral 1 designates a hollow standard rising from and suitably secured to a hollow base 2 which may well be provided with a door 3 for giving access to its interior. The upper end of the standard 1 carries a hollow head 4 which is preferably swiveled thereon, and although any preferred swiveled connection could be used, I prefer to provide 90 said head with a depending neck 5 rotatably received in the standard 1, and to both retain the neck in the standard and limit the rotary motion of the head, I have shown a semi-circular groove 6 in the neck and a screw 7 passing through the standard and received in said groove. The ends of the groove 6 coact with the screw 7 in limiting the turning of the head.

In most instances, I mount an electric light 105 8 and a globe 9 therefor, upon the head 4, but the principal office of the latter is to carry a vertically swinging arm 10 which is preferably of tubular form. One end of the arm 10 is shown extending through an open- 110

ing 11 in the head 4 of the standard 1, cap screws 12 or other suitable means being provided for pivotally mounting said arm. Any preferred means such as an elastic connection 5 is provided for normally holding the arm 10 in vertical position, but for permitting downward swinging thereof at will, and for illustrative purposes, I have shown a rod 13 and a spring 14, connected one to 10 the other, with the rod pivoted to the inner end of the arm 10 and the spring adjustably anchored at 14'.

The air hose 15 passes through the standard 1 and the arm 10 and depends from 15 the free end of the latter, which end is preferably curved as shown and provided with a resilient coiled hose protector 16 which prevents cracking of the hose at the point where it leaves the arm. The free 20 end of hose 15 is provided with any suitable connection 17 for application to the usual tire valve. Before this connection may be applied to the valve, it is necessary to first pull the hose 15 downwardly, and 25 this lowers the arm 10, placing the connection 13—14 under tension. As will be hereinafter described, this movement of the arm 10 serves to operate the control of the air supply means, thus causing the passage 30 of air through the hose to inflate the tire. When the hose is released, the arm automatically returns to its raised position to hold the hose suspended as seen in dotted lines in Fig. 1 and in full lines in Fig. 2, 35 and when this return of parts takes place, the air supply is automatically cut off.

In most instances, I prefer that the inner end of arm 10 shall be formed by a casting 18 extending through the opening 11 and 40 pivoted by the screws or the like 12, and this casting is formed with an opening 19 receiving the hose 15 and of such shape as to prevent injury to said hose during the swinging movement of the arm.

45 The hose 15 may lead from any suitable source of air pressure. In Fig. 3, a compressor 20 driven by an electric motor 21, is shown for supplying air to said hose, while in Fig. 6 I have diagrammatically 50 illustrated a tank 22 connected with said hose by a pipe 23 and a control valve 24. When the motor driven compressor 20 is used, it may well be located within the hollow base 2 and the control means for the 55 motor is also by preference in said base, said control means being here shown in the form of a switch having a vertically movable arm 25 and a fixed contact 26 with which it coacts, said arm and contact being 60 in circuit with the motor 21 for controlling the latter. A spring 27 normally moves the switch arm 25 downwardly away from the contact 26, but a spring 14^a and rod 14^b or any other connection which might be used 65 in lieu thereof, is attached to said switch

arm and to the arm 10 in such manner as to raise the former and close the switch, when placed under tension by a downward pull on said arm 10. The moment this arm is allowed to again ascend however, spring 70 27 opens the switch. It will thus be seen that whenever the hose 15 is pulled to a point at which it may be used for inflating a tire, the circuit of the motor 21 will be completed, so that said motor operates the 75 compressor 20 and supplies air through the hose 15. The motor however is automatically thrown out of play by return of the arm to its initial vertical position. The spring 14 is the primary power which raises 80 arm 10, but the springs 14^a and 27 assist.

When the arrangement illustrated in Fig. 6 is used, the valve 24 may be provided with an operating arm 28 to which a spring 29 is attached to normally close said valve, and 85 the connection 13—14 may then be connected with said arm in such manner as to open the valve when the arm 10 is swung downwardly. This allows the escape of compressed air from the tank 22 to which 90 it may be supplied by any preferred means such as the ordinary automatic compressor. When the arm 10 again swings upwardly, the spring 29 automatically closes the valve to prevent further escape of air. 95

If desired, the valve 24 may be omitted from the air line and an automatic check used on the end of the hose, as on the usual free air stations.

The invention may be installed wherever 100 required and will be highly efficient and in all ways desirable for the purpose intended. To operate the device, it is simply necessary to pull upon the hose 15 to lower the arm 10 to the most convenient position. 105 The air pressure is thus automatically supplied to the hose to inflate the vehicle tires, and when moving the hose from one wheel to another, the arm in question may swing horizontally, due to the swiveled connection 110 of the head 4 with the standard 1. The moment the hose is released and the arm 10 returns to its vertical position, the air pressure is automatically cut off.

I prefer in most instances to equip the 115 device with a hose 30 having a spigot 31, said hose being supplied with water from any suitable source through a pipe line 32 within the standard 1. Automobiles may thus not only be supplied with free air for the tires 120 but their radiators may be filled with water.

In Figs. 7, 8 and 9, the numeral 35 designates a vertical tubular standard which may be supported by a bracket 36, either from a ceiling as shown in Figs. 7 and 8 or 125 from a vertical wall as depicted in Fig. 9. The standard 35 carries a swiveled head 37 on its lower end, which head is shown provided with an inverted light 38 which illuminates the area below in order that 130

tires may be easily inflated at night. The head 37 carries a vertically swinging arm 39 which is shown of tubular form to receive an air hose 40 which may lead through the 5 standard 35 to any suitable pressure supply tank, compressor or the like. The free end of the hose 40 carries the usual automatic check 41 which normally prevents a discharge of air but permits such discharge 10 when applied to a tire valve. As in the forms of the device previously described, the arm 39 is normally raised, and I have shown a coil spring 42 for this purpose. One end of this spring acts against the inner 15 end of the arm 39 while its other end bears against a stop 43 on the upper end of a rod 44, which rod may be adjusted by a nut or the like 45 to vary the tension of the spring. A chain or the like 46 may be attached to 20 the hose 40 for pulling the same downwardly for use and when this operation takes place, the valve 41 may be applied to the tire valves in the usual way. The arm 39 may swing horizontally to permit inflation of any 25 of the tires.

The bracket 36 is by preference in the form of a tubular casting having an attaching flange 47 which may be secured to a vertical or horizontal support. The bore of 30 this casing receives the tubular standard 35 when said casting is used vertically as in Figs. 7 and 8, but when the flange 47 is secured to a vertical wall and the bracket thus positioned horizontally as seen in Fig. 9, 35 standard 35 is received in openings 48 with which the bracket is provided. In either instance, the set-screw 50 or other suitable means may be employed for locking the standard in the bracket.

40 In connection with the device just described, I might employ some form of switch and automatic air compressor controlled by the movement of the arm 39, but I prefer that the air pressure shall be constantly contained in the hose 40 and its discharge controlled by the valve 41.

In Figs. 10 to 13 I have illustrated a coin-controlled apparatus for locking the arm 39 against descent until the proper coin 50 is inserted, and since I might employ numerous arrangements for producing this result, the following description and the drawings are to be considered as typical only of one way of accomplishing the desired end.

55 I have shown a vertical rod 55 swiveled at 56 to the rod 13 and forming therewith a positive connection between the locking mechanism and the arm 10 when said mechanism is in active position. It will thus be 60 seen that the arm cannot be lowered until the rod 55 is released. I have shown a notch 57 near the lower end of the rod 55 to normally receive a sliding bolt 58 suitably mounted in guide portions 59 and 60 of a 65 bracket 61 which may well be located in the

base 2. A pivoted latch lever 62 is mounted on the bracket 61 and provided with a nose 63 adapted to engage a shoulder 64 of the bolt 58 and thus lock the latter in operative position. This lever however, is provided 70 with a lateral pin or the like 65 extending across a coin chute 66 so that when a nickel or other predetermined coin 67 is dropped into said chute, the latch 62 will be released, allowing the bolt 58 to be retracted by hand. 75

To prevent the latch 62 from being released by the coin and then returning promptly to active position before the bolt 58 can be released, I provide a stop 68 on said bolt, said stop serving to limit the movement of the lever 62 when the coin 67 is inserted, so as to trap said coin and cause it to hold the latch 62 in released position, until the bolt is retracted by hand. When this is done, however, the stop moves and permits 85 the latch to complete its movement and discharge the coin into a suitable coin-box 69 from which the coins may be removed from time to time.

To hold the bolt 58 in released position 90 against the tension of spring 70 which serves to project said bolt, I provide a pivoted dog or the like 71 to engage a shoulder 72 on said bolt, a spring 73 being shown for moving said dog to operative position when the bolt 95 58 is retracted from the notch 57. The mounting of the dog 71 preferably consists of a slot 74 in said dog and the pin 75 received in said slot and carried by the portion 59 of the bracket 61. This mounting 100 comes into play to allow the dog to tilt upwardly when the rod 55 rises and the lower end of its notch 57 strikes the end 76 of the dog. It is thus insured that the dog shall in no manner interfere with the ascent of 105 the rod 55 and downward movement of the arm 39, after the bolt 58 has once been retracted.

In addition to performing the function above described, the rod 55 may serve to 110 operate a switch mechanism for the motor 21 which drives the air compressor 20. In obtaining this result, I mount a switch actuating member 77 in position to be struck and moved downwardly by the rod 55 when the 115 spring 14 acts to raise the arm which carries the hose. I have shown the member 77 pivoted at 78 upon a part of the bracket 61 and provided with a spring 79 for raising it when the rod 55 is moved upwardly. Upward movement of member 77 is adapted to close the switch while downward movement thereof opens said switch. It will thus be seen that when the hose has been pulled 120 downwardly for use, after releasing the coin-controlled locking means, the switch will be closed to supply current to the compressor 21. The moment the hose is allowed to ascend to its normal position however, the switch automatically breaks the circuit. 125 130

- The switch above mentioned preferably consists of fixed and movable contacts 80 and 81 respectively, the former being rigidly carried by and insulated from the bracket 60, while the contact 81 may be mounted on a vertically swinging arm 82 pivoted to said bracket at 83 and guided in its vertical movement by appropriate guides 84. A coil spring 85 connects the free end of arm 82 with the switch operating member 77 and it is the pull which said member 77 exerts upon the arm 82, either above or below its center, that causes movement of said arm to operate the switch.
- 15 The wiring for the motor 21 may be connected in any suitable way with the contacts 80 and 81, for instance by the arms 86 shown in Fig. 11.
- The normal position of parts is shown in Fig. 11, the hose carrying arm being then raised so that the rod 55 is lowered with the result that the bolt 58 is received against the lower end of the notch 57, the nose 63 of the latch 62 is in engagement with the shoulder 64 to hold the bolt projected, and the switch operating member 77 is lowered to exert a downward pull on the arm 82 to separate the contacts 80 and 81. When a coin 67 is now inserted it strikes pin 65 as shown in Fig. 11 and rocks the latch 62 until it strikes the pin 68. This releases the nose 63 from the bolt 58 and allows the bolt to be retracted from the notch 57 by hand. The moment this retraction takes place, the dog 71 moves into engagement with the shoulder 72 and holds the bolt in released position. The rod 55 is now free to move upwardly allowing the hose and its carrying arm to move downwardly for use. During upward movement of rod 55, the lower end of its notch 57 will strike the end 76 of the dog 71 but the slot 74 permits said dog to then tilt upwardly, so that ascent of the rod 55 is not interfered with.
- 40 As rod 55 moves upwardly, spring 79 similarly moves the switch operating arm 77, thereby causing spring 85 to pull upon the arm 82 above the center of the latter, with the result that said arm swings upwardly and the contact 81 engages the other contact 80. This completes the circuit of the motor 21 with the result that it operates to drive the compressor 20 and supply air through the hose 15.
- 45 Should it be desired to hold the locking mechanism in released position so that the air hose could be used free of charge, a key may be inserted in a key-hole 90 and used to hold the latch 62 in released position so that bolt 58 may be retracted whenever desired, without the necessity of inserting a coin.
- 50 After use of the air hose, the spring 14 raises the arm 10 to its normal position and consequently the rod 55 lowers, striking the switch operating member 77 and lowering the same so that it pulls upon the spring 85 to open the switch, thereby arresting movement of the compressor. As the rod 55 lowers, the spring 73 moves the end 76 of the dog into engagement with the upper end of the notch 57, so that further downward movement of said rod will rock the dog and will release it from the shoulder 72. Spring 70 then acts to project the bolt 58 into the notch 57, so that all parts are locked against movement.
- 55 Since probably the best results may be obtained from the forms of construction shown, they may well be followed, but within the scope of the invention as claimed, numerous minor changes may well be made, and it will be understood that although I prefer to equip the device with means for supplying water, in addition to air, this water supply means may well be eliminated, if desired.
- 60 I claim:
1. An air supply station for motor vehicles comprising the combination of air supply connections terminating in a flexible length of hose provided at its outer end with a valved head adapted to fit a tire nipple, a movable supporting member for the other end of said length of hose adapted to swing over a vehicle canopy and carry the hose to positions convenient for tire inflating operations, and means for automatically retracting said supporting member and hose to a normal position of suspension at one side of the path of vehicle travel said hose also constituting means for manipulating the supporting member from normal position.
  2. An air supply station for motor vehicles comprising a standard, a normally raised but downwardly movable arm pivoted to said standard, and an air supply hose extending along and having a free portion depending from the free end of said arm, means for permitting a manual adjustment of said arm above a roadway, and means for automatically retracting it from above the roadway when manually released.
  3. An air supply station for motor vehicles comprising the combination with a standard, an arm normally supported therefrom in a raised position and adapted to swing both vertically and laterally, means for yieldingly holding said arm in said normal position, an air supply connection extending along said standard and arm, and having a flexible portion normally suspended from the extremity of said arm in close proximity to the standard, said arm being adapted to swing downwardly and also laterally from its normal position under a pull exerted upon the air supply connection, the arrangement being such that the standard may be used to support the air supply connection between the side walk and curb.

- lines of a street and allow said connection to be carried outwardly by a downwardly swinging movement of the arm over and around a vehicle in the street.
5. An air supply station for motor vehicles comprising the combination with a standard and an air supply connection, including a hose at its delivery end, a valved head adapted to engage a tire nipple, means 10 for normally supporting said hose and valved head in close proximity to the standard, said means being also adapted for yieldingly supporting the outer portion of said hose and valved head in a suspended position at a distance from the standard and along different radial lines to facilitate the adjustment of the valved head to tire nipples carried by the wheels of a vehicle adjacent to said station.
10. An air supply station for motor vehicles comprising the combination with a support, of an arm connected therewith and adapted to swing both vertically and laterally, an air supply connection extending 15 from the support along and beyond the end of said arm and having a flexible portion provided with an extremity adapted to be fitted to a tire nipple, and yielding means for automatically swinging the arm to a raised position with the extended end portion of the air supply connection in close proximity to the support and in a position to be manually grasped, to draw the supporting arm outwardly and downwardly 20 over a vehicle located beyond the normal position of the arm and its supply connection, whereby, when the supply connection is released, it will be held out of contact with the earth and returned to its normal raised 25 position out of the path of the vehicle.
6. An air supply station for motor vehicles comprising a tubular standard having near its upper end an opening, a normally raised but downwardly movable tubular arm 30 extending at one end through said opening and pivotally mounted therein, an air supply hose extending through said standard and arm, and depending from the outer end of the arm, and means in said standard connected with said arm for normally raising the latter.
7. An air supply station for motor vehicles comprising a standard, a normally raised but downwardly movable arm pivoted 35 to said standard, and an air supply hose depending from the free end of said arm; together with air supply means for said hose, means connected with and actuated by said arm for controlling said supply means, and a valved head at the outlet end of the 40 hose for engagement with and actuation by a tire nipple.
8. An air supply station for motor vehicles comprising a standard, a normally raised but downwardly movable arm pivoted 45 to said standard, and an air supply hose depending from the free end of said arm; together with air supply means for said hose, means connected with and actuated by said arm for controlling said supply means, and a valved head at the outlet end of the 50 hose for engagement with and actuation by a tire nipple.
9. An air supply station for motor vehicles comprising a standard, a normally raised but downwardly movable arm pivoted to said standard, and an air supply hose depending from the free end of said arm; together with an electrically driven compressor for supplying air to said hose, a switch in circuit with the driving means of said compressor, and means connecting said switch with said arm for controlling the former from the latter.
10. An air supply station for motor vehicles comprising a standard, a normally raised but downwardly movable arm pivoted to said standard, and an air supply hose depending from the free end of said arm; together with an electrically driven compressor for supplying air to said hose, a switch in circuit with the driving means of said compressor, and means connecting said switch with said arm for controlling the former from the latter and for assisting in raising said arm.
11. An air supply station comprising a normally raised but downwardly movable pivoted arm, and an air supply hose depending from the free end of said arm; together with air supply means connected with said hose, control means for the air supply, and an elastic connection between said control means and said arm for both actuating the former and assisting in raising the latter.
12. An air supply station comprising a normally raised but downwardly movable pivoted arm of tubular form, and air hose extending through and depending from the free end of said arm, and a resilient coiled protector secured to said free end of said arm and surrounding said hose.
13. A tire inflating station comprising a standard, a normally raised hose carrying arm pivotally mounted on said standard and adapted to swing downwardly to render the hose accessible for use, and coin controlled means for normally preventing use of said hose.
14. In a tire inflating device, a hollow standard, a vertically swinging arm mounted on said standard, a tire inflating hose depending from the free end of said arm, means for normally raising said arm, a rod connected with said arm and located in said

hollow standard, and coin-controlled means acting on said rod for normally locking the device against operation.

15. A device of the character described including a standard, a swivel bracket on said standard, an arm pivoted to said bracket disposed for vertical swinging movement

with respect thereto, counter balancing means on one end of said arm and a supply hose carried by said standard and by the 10 other end of said arm.

In testimony whereof I have hereunto set my hand.

ARNO A. EWALD.
